UNITED STATES PATENT OFFICE.

WILLARD H. GILMAN, OF MEDFORD, MASSACHUSETTS, ASSIGNOR OF ONE-HALF TO WILLIAM H. GANNETT, OF AUGUSTA, MAINE.

INDEX.

SPECIFICATION forming part of Letters Patent No. 732,679, dated June 30, 1903.

Application filed June 16, 1902. Serial No. 111,867. (No model.)

To all whom it may concern:

Be it known that I, WILLARD H. GILMAN, of Medford, in the county of Middlesex and Commonwealth of Massachusetts, have invented certain new and useful Improvements in Indexes, of which the following is a specification.

The object of the present invention is to provide an improved form of index to take the place of the card system now in vogue, as well as to supersede the forms of book-indexes now in use.

In most indexes where cards or leaves are divided into groups under general indexing-symbols and the cards or leaves of each group subindexed it is the custom to have the individual card or leaf index denote the second letter or first vowel in a name, or it may be the second numeral of a figure. The prevailing system of the character indicated greatly limits the capabilities of an index, not only by restricting subdivision, but also by precluding uniform distribution of entries.

My invention provides for subindexing by the third letter of a name, which greatly enlarges the capabilities of an index by permitting more extensive subdivision, as well as by affording opportunity for a more nearly uniform distribution of entries by groups.

Furthermore, my invention provides for an index structure of extreme flexibility capable of being easily carried in one hand and at the same time manipulated while moved over a set of books, a complete index structure being made possible by my invention which will be so short, measured from top to bottom, so comparatively thin, and so flexible that it can be grasped at the middle of its width, the hand spanning the index, while the thumb may be employed to open the index at different places, all while the subindexing-symbols of an entire group are kept in sight. In such an embodiment of the invention the index will preferably be in book form, permanently bound. However, where the invention is to be substituted for the card system or is to provide in itself a medium for keeping accounts provision is made for removing ability of leaves on which individual entries are carried, and in this connection the inven-

tion embraces a special construction of base-support for the index structure which allows of the leaves being turned over independently of each other, so that the entire page 55 is easily accessible for making entries and exposable for reading the same. When embodied as last indicated, the invention embraces a second subindexing—viz., indexing of groups of leaves for individual entries 60 when arranged between the members of a group of leaves themselves subindexed under a general heading.

Further, the invention provides for combining in one structure two kinds of indexes, 65 one governed by a single subindexing and the other by a second subindexing under the same first subindex.

With the above-stated and other incidental objects in view the invention consists in 70 certain novel arrangements of parts and features of construction, the essential elements whereof are recited in the appended claims and preferred forms of embodiment whereof are specifically described hereinafter and 75 illustrated in the accompanying drawings, whereof—

Figure 1 represents in cross-section a portion of a drawer with index structures therein embodying my invention. Fig. 2 represents the same in plan view. Fig. 3 represents one of the indexing structures removed from the drawer and in plan with the top leaf turned back. Fig. 4 is a fragmentary edge or side view, on a reduced scale, of a modified form of index structure, showing portions of the spacing-leaves. Fig. 5 is an isometric representation of an index-book embodying the invention with the cover and first index-leaf thrown back and a number of 85 groups of indexing-leaves lifted.

In Figs. 1 to 3 the invention is shown embodied in a system designed to take the place of the well-known card system, wherein the cards are generally arranged in subdivisions 95 of drawers, and in Fig. 1 the reference-letter *a* designates such a drawer. The form of index here shown comprises a base-board *b*, adapted to lie flatly against the bottom of the drawer and having a series of shoulders *b'* in 100 planes at right angles to the bottom surface of the board and formed with sloping or in-

clined backs b'' . A set of leaves c , preferably of comparatively heavy material, are permanently fastened to said backs b'' by glue or otherwise, and these leaves overlap at 5 their outer ends, so that each leaf will have a marginal portion c' , protruding beyond the leaf in front sufficiently to bear inscriptions visible without lifting any of the leaves. The front or top leaf c is of somewhat heavier 10 material than the others, and a back leaf c'' of similar material is fastened to the back edge of the block b , said edge being beveled on the same angle as the backs of the shoulders. The marginal portions c' of the leaves 15 are preferably inscribed with the letters of the alphabet in their regular order and distributed according to the character of the indexing to be done and the frequency with which certain third letters will be encountered 20 in names. The whole set of leaves c will be grouped under a general head as a single letter of the alphabet, or it may be a number of letters, here shown as inscribed upon a tab or ear d , fastened to the first leaf 25 in such a way as not to hide any of the letters on the marginal portions c' of the leaves. Between the leaves c groups of loose leaves or cards e are placed with their inner edges abutting the shoulders b' , each of such groups 30 of loose leaves being covered normally by one of the leaves c . The loose leaves of a group are cut back in gradation at their outer edges, so as to form stepped ears or tabs e' , and if the limited length of the leaves or 35 cards does not permit the exposure of portions of all of the loose leaves or cards used by means of one set of these stepped ears with room enough for the desired inscriptions the group of loose leaves may be divided into two or more sets, each cut back as 40 described, and I have here shown such an arrangement, the under set of loose leaves e^2 being sufficiently longer than the upper set to protrude beyond the same the width of the 45 tabs or ears. (See Fig. 3.) Thus the ears of all the leaves will be disclosed when the covering-leaf c is raised.

In indexing names with the above-described form of embodiment of the invention each 50 name is given a separate loose leaf e , on which an account may be kept or data entered. The tabs or ears e' bear the initials of the names, and the third letters of the names are indicated by the letters on the marginal portions 55 c' of the leaves c , while the first letters of the names are indicated by the inscription on the tab d .

Of course it is to be understood that the device above described is but one of a sufficient 60 number to make a complete alphabetical index and in each division of a drawer, as a , a number of index structures may be assembled, one behind another, as shown in Fig. 1, and the marginal inscriptions on the leaves 65 c of each will be visible, as well as all the tabs d , as shown by Fig. 2. It will be seen that any one of the index structures can be taken

out bodily and replaced at pleasure without disturbing any others, and the subdividing-leaves c turn back easily, each on its own distinct line of flexure without obstruction by any other leaf or leaves. Then the loose leaves or cards work independently and not only can be turned and laid back readily, but any one of them can be removed altogether and replaced. In this form of embodiment of the invention (illustrated by Figs. 1 to 3) the subdividing-leaves are preferably blank, as they are not designed to receive entries, all entries being made on the loose leaves or cards. 70 However, it is within the scope of the invention to dispense with groups of leaves between the overlapping alphabetically-inscribed leaves and to use the latter for entries of names, and in Fig. 5 the invention is shown 75 so embodied. Here reference-letter c^2 designates the overlapping leaves, which in this instance are superposed one directly over another and bound together in any suitable manner either temporarily or permanently 80 within covers f , the front one of which is shorter than the back, so as to expose a set of general indicating-tabs d^2 . The leaves c^2 of a group are graduated in length to provide the successively-overlapping marginal portions c^3 , bearing alphabetical inscriptions. 85 As this book-form structure is to comprise a complete index in itself, there are as many groups of these overlapped leaves as needed for the tabs d^2 , which indicate first letters of 90 names. One of these tabs is fastened to a blank leaf d^3 , extending over each group except the first or top one, and the tabs are relatively positioned, so as to all show at once one below another, and by lifting any tab and 95 turning back the portion of the book above it one complete set of overlapping alphabetically-inscribed third-letter-indicating set of leaves is disclosed.

It will be seen that an index-book such as 100 above described can be made comparatively short, measured from top to bottom, and yet have great capacity, while affording unusual facility for manipulation, since it can be carried in one hand and moved over a set of 105 books handily. The overlapping arrangement of leaves provides for indicating-inscriptions, which will also designate the part of the leaf where entries will be found—as, for example, on the leaf marked "A B C" the upper part would have names the third letter of which is "A," while the middle part would bear names the third letter of which is "B," and the lower part names the third letter of which is "C."

A book such as above described may be constructed to carry additional leaves between the alphabetically-inscribed leaves after the manner illustrated in Figs. 1 to 3, so as to have in a single structure two types 110 of index, one for the indexing as to entries on the alphabetically-inscribed leaves themselves and the other for indexing as to entries on the loose interposed leaves without 115

regard to the entries on the alphabetically inscribed leaves, but governed by the indexing-inscriptions thereon.

While throughout this description names are referred to as the subject-matter for indexing, it will be understood that the invention may be utilized for various kinds of indexing.

The spacing apart of the leaves to accommodate loose leaves may be provided otherwise than by shouldering the base-blocks, and in the construction shown by Fig. 4 this spacing is accomplished by bending or folding back the inner edges of leaves c^4 and securing the folded-back portions c^5 against the surface of a plain base-block b^2 .

It is obvious that a number of index structures embodying the invention might be arranged one below another in making up an index, so that they would be separately removable, thereby enabling more than one person to use the index at a time.

In the practical operation of this device, referring first to Fig. 5, it is to be understood that the first leaf of the series, which carries the master-indicator "A B," has been turned over, so as to expose the overlapped marginal portions of the other leaves of the series. These overlapped marginal portions are elongated in the sense that they extend practically the full width of the leaves, and said overlapped marginal portions bear a plurality of symbols, all of which are visible simultaneously even when the leaf carrying the master-indicator is superposed thereon. The letters on the master-indicator designate the series which are to bear names beginning with "A" or "B," while the symbols borne by the ex-

posed marginal portions of the other leaves designate in a preferred use of the invention 40 the third letters occurring in said names. Therefore the user can at once determine the location of an entry, owing to the fact that there are simultaneously exposed before him the indicators of both the first and third letters of the name-entry sought.

Having thus described certain ways of embodying my invention, without intending to limit myself to the same, what I claim as new is as follows:

1. An index structure comprising a series of leaves permanently connected and having a master-initial indicator for designating the first letter of names having the same initial, the said leaves having overlapping edges 55 forming elongated simultaneously-visible marginal portions provided with a plurality of subinitial-indicators, and blanks operatively arranged in relation to said subindicators for the inscription of names designated by said subindicators.

2. An index structure comprising a base having a series of shoulders with inclined backs, indicator-leaves fastened to the latter and groups of loose leaves or cards between 65 said indicator-leaves, the inner edges of the loose leaves abutting the shoulders.

In testimony whereof I have signed my name to this specification, in the presence of two subscribing witnesses, this 14th day of 70 June, A. D. 1902.

WILLARD H. GILMAN.
